Primary Examiner — Karen S Acker(74) *Attorney, Agent, or Firm* — Thomas C. Feix(57) **CLAIM**

The ornamental design for a sheet material with pattern, as shown and described.

DESCRIPTION

The sole FIGURE is a front view of a sheet material with pattern showing my new design.

The surfaces of the sheet material with pattern that are not illustrated in the drawing or described herein do not form a part of the claimed design.

The broken line perimeter surrounding the design indicates the boundaries of the claim and forms no part thereof.

The broken lines form no part of the claimed design.
